Bancker & Campbell,

Converting Motion.

No 21934.

Patented Nov. 2, 1858.

UNITED STATES PATENT OFFICE.

GERARD BANCKER AND ANDREW CAMPBELL, OF NEW YORK, N. Y.

IMPROVEMENT IN MECHANISM FOR TRANSMITTING ROTARY MOTION.

Specification forming part of Letters Patent No. 21,934, dated November 2, 1858.

To all whom it may concern:

Be it known that we, GERARD BANCKER and ANDREW CAMPBELL, of the city, county, and State of New York, have invented certain new and useful Improvements in Mechanism for Obtaining Rotatory Motion from a Rectilinear Motion; and we do hereby declare the following to be a full description of the same.

The nature of our invention consists in attaching to the frame of a crank-shaft an extension-rod having on its lower end a friction-roller, over which and another roller secured on the crank-shaft is arranged an endless belt or band. This is operated by means of a sliding clamping-block on the extension-rod, in combination with a double-acting clamping-lever the fulcrum of which is secured in the sides of the clamping-block, so that as the outer end of the clamping-lever is operated by a piston-rod or other rectilinear motion the clamping-edges of the clamping-lever alternately impinge one side of the belt against the clamping-block, which, sliding up or down, as the case may be, on the extension-rod, causes the belt to rotate, and thus by clamping alternately the opposite sides of the belt at each half-stroke of the piston-rod keep up a continuous motion in the crank-shaft.

To describe our invention more particularly we will refer to the accompanying drawings, forming a part of this specification, the same letters of reference, wherever they occur, referring to like parts.

Figure 1 is a side view of the apparatus as applied to the crank-shaft. Fig. 2 is an edge view of the apparatus and belt. Fig. 3 is a plan view of the apparatus and belt through the line $x x$, Fig. 2.

Letter A is a crank-shaft arranged in any suitable frame B for propelling purposes. Attached to the frame is a rod C of any required length, and having at its lower end a friction-roller D, over which and a second roller or pulley E on the crank-shaft is an endless band F for transmitting rotary motion to the crank. To do this a sliding clamping-block G is adjusted on the rod C, so as to allow it to slide up and down on the rod be-

tween the sides of the endless band and the friction-rollers at the end of the rod and on the crank-shaft. Attached to this clamping-block, and at right angles to it, is secured by a center pin H a clamping-lever i, the sides of which are joined together by braces j and k, so as to inclose or embrace the opposite sides of the endless band, but leaving space enough between them and the sides of the clamping-block for the free passage of the alternate sides of the band when not clamped by the action of the piston-rod L on the outer end M of the clamping-lever. It will be observed that the brace j is not on a line with the edge of the brace k, and both are above the axis or fulcrum of the lever. The object of this arrangement is to cause the braces to impinge the band against the sides of the clamping-block at each alternate stroke of the piston instantly on the reversal of its motion.

The operation of the apparatus is that when the piston-rod attached to the outer end of the clamping-lever is moved downward in the direction of the arrow, Fig. 2, it causes the brace k to clamp one side of the band against the clamping-block and releases the opposite side of the band from the clamping-brace j, and as the clamping-block is then permitted to slide on the rod C, the whole is carried forward to the end of the stroke of the piston to revolve the crank-shaft. Immediately the stroke of the piston is reversed the end M of the clamping-lever is forced upward, so as to cause the clamping-brace j to impinge the band against the clamping-block, and at the same time releasing the band from the clamping-brace k, so as to allow the return-stroke of the piston to be made, and thus continue the revolution of the crank-shaft and keeping up a continuous rotatory motion therein.

Letter P is a fly-wheel attached to the crank-shaft. This fly-wheel is not material for various purposes to which the apparatus may be applied; but where much leverage is exerted by the crank of the crank-shaft for propelling purposes it is deemed best to use the fly-wheel as securing a more steady motion.

Having now described our invention and its operation, we will proceed to set forth what we desire to secure by Letters Patent of the United States.

What we claim is—

The use of the combination of the sliding-clamping-block G and extension-rod C with the double-acting clamping-lever, made and

operated in the manner and for the purposes hereinbefore set forth.

GERARD BANCKER.
A. CAMPBELL.
